(57) **CLAIM**

The ornamental design for an emergency release unit, as shown and described.

DESCRIPTION

FIG. 1 is a front elevational view of an emergency release unit showing my new design, the rear elevational view being a mirror image thereof.

FIG. 2 is a front, side perspective view thereof.

FIG. 3 is a front, bottom, side perspective view thereof.

FIG. 4 is a front, top, side perspective view thereof.

FIG. 5 is a front perspective view of the upper part thereof,

with the lower part being removed for clarity; and,

FIG. 6 is a front perspective view of the lower part thereof,
with the upper part being removed for clarity.

1 Claim, 6 Drawing Sheets
